UNITED STATES PATENT OFFICE.

JOHN A. KURTZ, OF ALLEGHENY, PENNSYLVANIA, ASSIGNOR TO JAMES R. McCLELLAND, OF SAME PLACE, AND ALBERT PANTZER AND H. H. SCHULTE, BOTH OF GLENFIELD, PENNSYLVANIA.

SEAL-LOCK.

SPECIFICATION forming part of Letters Patent No. 417,568, dated December 17, 1889.

Application filed August 22, 1889. Serial No. 321,673. (No model.)

To all whom it may concern:

Be it known that I, JOHN A. KURTZ, of Allegheny, Pennsylvania, have invented a new and useful Improvement in Seal-Locks, which improvement is fully set forth in the following specification, reference being had to the accompanying drawings.

Similar letters of reference indicate corresponding parts.

10 The object of my invention is a seal-lock for use of railroads—that is, on freight-cars, for use of the United States mail-service, or such other purposes to which it is applicable.

I am aware that it is not new to provide a 15 seal-lock with a rotary cylinder having an eccentric groove and fitted in a chamber in one end of a bow or shackle, the inner surface of the chamber being corrugated or roughened, said cylinder being limited to turn in one direction by means of gravity-pins, which are 20 fitted in the cam-groove of said cylinder and adapted to bind in said groove and against the roughened surface of the cylinder, and such construction I therefore disclaim.

25 My improvement consists of a spring-actuated locking-pin seated in a recess at right angles to the axis of the rotary cylinder and normally projected into the path of an abrupt shoulder formed by a cam-groove on the periphery of the cylinder, said locking-pin being concealed at all times and protected from the weather by the rotary cylinder, which fits snugly in the chamber formed in the shackle or bow.

30 In the accompanying drawings, Figure 1 shows one of my locks with all its parts in place. Fig. 2 is an enlarged detail view in elevation of a part of the shackle or bow and the frangible seal-plate, showing the positions of said parts when they are adjusted for use. Fig. 3 is a view of the grooved cylinder, showing the handle B'. Fig. 4 is the 35 frangible seal-plate, and Fig. 5 is a cross-section of the part B.

40 A is the shackle or bow of my improved seal-lock, which comprises the two wings a', the wing a being provided with a transverse mortise for the reception of the tenoned end 45 of the frangible seal-plate A', while the other

wing a' is formed with an eye or loop a² to 50 receive a chain or other suitable fastening, and with a cylindrical chamber B. This chamber is reamed out, so as to admit the cylinder b. This cylinder has a groove b⁴, cam-shaped, forming the shoulder b³. b' is a 55 pin, and b² is a spring. This pin is placed in a recess in the wing a', bored out for the purpose. The spring b² is first placed in this recess, and then the pin b' is put therein. Then when the cylinder b is put into its place in 60 the chamber B this pin b' springs into the groove b³. It will be seen that this cylinder b, with the pin b' in the groove, can be made to revolve continually only one way, for if it is attempted to reverse it the pin soon stops 65 against the shoulder b³.

When the frangible seal-plate A' is in place, as seen in Fig. 1, the tenoned end a³ will be 70 in the mortise prepared for it, and the forked end a⁴ will be placed between the side of the cylinder b and the handle B' at b⁵. Then as the handle is turned round till it stops at the post a⁵ the pin b' falls into or stops at the shoulder b³, and hence the arm B' can move 75 neither way, as it is prevented from turning one way by the post a⁵ and the other way by the shoulder b³, and as the frangible seal-plate A' is thus locked into position or place and cannot be taken out by any manipulation of the lock it will be necessary to break 80 it, (the frangible seal-plate A'). This breaking of the frangible seal-plate A' to open the lock is the design of my invention. These frangible seal-plates A' will be made of iron 85 of sufficient brittleness to be broken by a moderate blow. They are only intended to be used once; but, being made very cheaply, this is not much of an objection.

Having thus described my invention, what I claim, and desire to secure by Letters Patent of the United States, is—

As an improvement in seal-locks, a shackle or bow having a chamber formed in one arm thereof, the inner surface of which is smooth, a rotary cylinder fitted snugly in said chamber and adapted to turn freely therein, and having a peripheral cam-groove which terminates in an abrupt shoulder, and a spring-

actuated locking-pin b' , seated in a recess b^2 , formed in the shackle or bow at right angles to the axis of the cylinder, said pin being normally projected toward the cylinder and 5 in the path of the abrupt shoulder thereon, for the purpose described, substantially as set forth.

Having thus described and claimed the above as and for my own invention, I hereto set my hand in presence of two witnesses.

JOHN A. KURTZ.
